UNITED STATES PATENT OFFICE.

LOUIS V. HOMAN, OF SOUTH DARTMOUTH, MASSACHUSETTS.

POWER-OPERATED SLIDING DOOR.

1,332,727.

Specification of Letters Patent.

Patented Mar. 2, 1920.

Application filed October 6, 1919. Serial No. 328,813.

To all whom it may concern:

Be it known that I, LOUIS V. HOMAN, a citizen of the United States, residing at South Dartmouth, in the county of Bristol and State of Massachusetts, have invented new and useful Improvements in Power-Operated Sliding Doors, of which the following is a specification.

This invention relates to a sliding door, operated by power and particularly to the type of door operating mechanism disclosed by my Patent 1,315,308, dated September 9th, 1919, said mechanism including a reversible motor, and motion-transmitting connections between the motor and a sliding door, and adapted to alternately open and close the latter.

The invention has for its object to provide improved means for yieldingly arresting the door at each end of its path, and is embodied in the improvements hereinafter described and claimed:

Of the accompanying drawings forming a part of this specification,—

25 Figure 1 is a side view of a portion of a building looking outwardly, and showing a door, a motor and a door check embodying the invention.

30 Fig. 2 is a sectional view of one of the dash pots, hereinafter described.

The same reference characters indicate the same parts in all of the figures.

In the drawings, 12 represents the front wall of a building or compartment such as 35 a garage, having a doorway 13. 14 represents a door adapted to open and close the doorway, the door being of the sliding type and provided with suitable hangers 15, the wheels of which are adapted to run on a 40 track 16, the door being suspended from the track.

17 represents the casing, and 18 the shaft of a reversible motor, which may be of any suitable character, the motor being preferably a reversing field electric motor of well known construction, and having a controlling member which is the arm 20 of a reversing switch, said arm projecting through a slot 19 in the casing. The motor is fixed 50 to the building adjacent to one end of the path of the door.

Connections are provided between the switch arm 20 and the door 14, through which the motor is operable to open and close 55 the door. As here shown, said connections comprise a pulley 21, which may be either

fixed on or geared to the shaft 18, and a cable 22 wrapped around the pulley to engage the latter without slipping, and attached at one end to an eye 23 fixed to the 60 rear portion of the door, and at its opposite end to an eye 24 fixed to the forward portion of the door, the cable passing around a guide pulley 25, journaled in a fixed support near the doorway. The arrangement is 65 such that when the motor runs in one direction the door is opened, and when the motor runs in the opposite direction the door is closed.

Fulcrumed at 26 to a fixed support above 70 the door way is a switch lever 27, which is connected by a rod 28 with the switch arm 20, and is adapted to move said switch arm to different positions. When the switch arm is in one position, the motor shaft runs 75 in the direction required to close the door, and when the switch arm is in another position, the shaft runs in the direction required to open the door. I have provided means operable from a plurality of locations spaced 80 from the door way.

When the switch arm is in an intermediate position the motor is stopped. The foregoing description is taken from the specification of my former patent. The switch arm 85 may be moved by the means disclosed by the above mentioned patent, said means including manually operable pull cords 29 and 30, portions of which are shown by Fig. 1, and ears or projections 50 and 51, attached to 90 the door and adapted to contact with the switch arm. For a fuller description of said means and the mode of operation thereof, reference is made to the specification and drawings of said patent.

95 In carrying out the present invention, I provide a door checking or stopping means preferably constructed as next described.

31 and 32 represent cylinders fixed to the building at opposite ends of the doorway 100 13. In each cylinder is a movable piston 33, having a member 34, such as a piston rod, arranged to contact with the door when the latter is approaching one end of its path. The outer end portions of the cylinders 105 32 and 33, are connected by a pipe line or conduit 35.

The cylinders and conduit contain a body of fluid a portion of which is shown at 36 in Fig. 2. Said body which is preferably a 110 non-congealable liquid, such as oil, fills the portions of the cylinders between their outer

ends and the pistons, and also fills the conduit, the portions of the cylinders between their inner ends and the pistons being empty or substantially so. Each cylinder, its piston, and its contact member 34, constitute a dash-pot adapted to yieldingly arrest the door at one end of its movement, one of said contact members being arranged to be moved by the door when the latter is approaching the end of its opening movement, and the other end being movable by the door, when the latter is approaching the end of its closing movement. A portion of the fluid is therefore forced out of the cylinder 32 and another portion into the cylinder 31, by the opening movement of the door, and a portion of the fluid is forced out of the cylinder 31 and another portion into the cylinder 32, by the closing movement of the door. To regulate the flow of fluid through the conduit 35, I provide said conduit with a throttle valve 38, or if desired, with two throttle valves, as shown by Fig. 1.

I claim:

25 1. A double acting door check, comprising two dash-pots, located at opposite ends of the path of a sliding door, each dash-pot including a cylinder, a piston therein and a

contact member connected with the piston and arranged to be moved by the door when the latter is near one end of its path, and a conduit connecting the outer end portions of the two cylinders, said cylinders and conduit containing a body of fluid, which is movable by the piston of either dash-pot 35 to transfer a portion of the fluid to the cylinder of the other dash pot.

2. A double acting door check, comprising two dash-pots, located at opposite ends of the path of a sliding door, each dash-pot including a cylinder, a piston therein and a contact member connected with the piston and arranged to be moved by the door when the latter is near one end of its path, and a conduit connecting the outer end portions of the two cylinders, said cylinders and conduit containing a body of fluid, which is movable by the piston of either dash-pot to transfer a portion of the fluid to the cylinder of the other dash-pot, means being provided for 50 regulating the flow of fluid from each cylinder to the other.

In testimony whereof I have affixed my signature.

LOUIS V. HOMAN.
